UNITED STATES PATENT OFFICE.

CLAYTON E. FREDERICKSON, OF CHICAGO, ILLINOIS, ASSIGNOR OF ONE-HALF TO
GRACE C. STENGER, OF CHICAGO, ILLINOIS.

TWO-CYLINDER TWO-CYCLE INTERNAL-COMBUSTION ENGINE.

1,183,549.

Specification of Letters Patent.

Patented May 16, 1916.

Application filed June 3, 1915. Serial No. 31,964.

To all whom it may concern:

Be it known that I, CLAYTON E. FREDERICKSON, residing at Chicago, in the county of Cook and State of Illinois, have invented 5 certain new and useful Improvements in Two-Cylinder Two-Cycle Internal-Combustion Engines, of which the following is a specification.

My invention relates to certain new and 10 useful improvements in the art of internal combustion engines, and the invention particularly relates to the two cycle class of engines having a charging pump separate from the working cylinders.

15 In its generic nature, the invention has for its object to provide an engine of this character of a simple and efficient construction and designed with a minimum number of parts and with the parts so arranged as 20 to be less liable to become disordered.

In its more detail nature, the invention comprises two working cylinders and a pumping cylinder, the pumping cylinder being double acting to charge the respective 25 working cylinders on each stroke of the pump piston, the pump piston being connected with a guide piston which also functions as an oil pump to insure circulation of lubricant to the various bearings.

30 In its more detail nature, the invention includes those novel details of construction, combination and arrangement of parts, all of which will be first fully described, then be specifically pointed out in the appended 35 claims, and illustrated in the accompanying drawings, in which:—

Figure 1 is a side elevation of the intake side of the engine embodying the invention.

Figure 2 is a vertical cross section on the 40 line 2—2 of Figure 1.

Figure 3 is a vertical cross section on the line 3—3 of Figure 1.

In the drawings, in which like numerals of reference indicate like parts in all of the 45 figures, 1 represents the crank case which may be of any approved construction, and is provided with openings into which the projecting ends of the several cylinders 2, 3 and 4 are seated, the cylinders 2, 3 and 4 50 being suitably fastened to the crank case in any approved manner.

The cylinders 2 and 3 are the working cylinders and are suitably water jacketed as at 5 for cooling purposes, in the usual

manner, while the cylinder 4 is designed to 55 act as the pumping cylinder.

6—7 designate the working pistons that operate in the cylinders 2 and 3, respectively and 8 designates the connecting rods of the working pistons which are connected with 60 the crank shaft 9 in the usual manner.

Each working cylinder is provided with a compression space 10 and an inlet 13 leading to the compression space. The inlets 13 are controlled by valves 23 hereinafter 65 again referred to.

Each working cylinder 2 and 3 is also provided with an exhaust port 14 which is controlled by the respective working piston, the exhaust ports 14 of the two cylinders 70 communicating with the exhaust manifold 15.

Each compression space inlet 13 of the working cylinders is connected with a duct 19. The ducts 19 have flanges 17 through 75 which fastening screws 18 are passed to secure the ducts to the machined faces 16 of the respective working cylinders over the respective inlets 13.

Each duct 19 is provided with valve stem 80 guides 20—21 in alignment with the inlet 13 of the respective cylinder. The valve 23 has its stem 24 passed through the guide 20 and into the guide 21 and is normally held seated by a light spring 25 that engages an 85 adjustable nut and collar on the stem. The valve stem guides 21 are closed at their outer ends by plugs 22. Each duct 19 has an opening 26 over which the valve seat member 27 is fastened, the valve seat member 27 being provided with a guide 28 in which the stem 30 of the valve 29 is located, a light spring 31 serving to keep the valve 29 seated. The valve 29 controls the passage of fuel from the intake manifold 32 which 90 is flanged at its ends as at 33 and is secured to the respective ducts 19 and valve seat members 27 by cap screws 34, as best shown in Figure 1 of the drawings.

The intake manifold 32 is provided with 100 the flanged entrance 35 that is designed to be secured to the carburetor, (not shown).

Each duct 19 has a flanged mouth 36 designed to be bolted at 37 over the upper and lower ports 38 of the pumping cylinder 4. 105

The pumping cylinder 4 is divided into two compartments 49—50 by the pumping piston 39 and the cylinder 4 seats in a recess

41 of the extension 40 which serves as a cross head guide for the guide piston 46.

42 is a connecting rod that joins the pumping piston 39 with the cross head guide piston 46, the rod 42 being screw threaded at 5 into the piston 46 and passes through a stuffing box formed by the neck 43 which 10 closes a metallic packing and is capped at 44.

47 is the connecting rod that joins the 15 piston 46 with the middle crank of the crank shaft 9, it being understood that in the form shown in the drawings, the stroke of the pump piston is less than that of the working piston and the cross sectional area of the 20 pump cylinder is correspondingly greater than that of the working cylinders.

48 is the space above the cross head piston 46, which space I prefer to utilize as an oil pump whereby oil may be drawn from 25 the reservoir 49 into the crank case through a pipe 58 that has a back check valve 51 and delivers the oil through the port 52 of the cylinder section 40, the discharge of the oil from the chamber 48 being effected through 30 the pipe 53. The pipe 53 is also provided with a back check valve 54 and delivers the oil into lateral pipes 56 that convey the oil to the various bearings which it is desired to lubricate.

35 In operation, on the down stroke of the pump piston 39, a new charge is drawn into the chamber 49 through the duct 19 that communicates with the end of the intake manifold 32 and that delivers into the working cylinder 3, the charge being passed from the carburetor into the manifold 32 through the valve 29 of the cylinder 3 and duct 19 into the upper chamber 49 of the pumping cylinder 4. At the same time, the charge 40 in the chamber 50 of the pumping cylinder is forced into the left hand duct 19 of Figure 1 during the upstroke of the piston 6, and is admitted into the working cylinder 2 through the valve 23 and compressed into 45 the compression space 10 of that cylinder. As soon as the piston 6 has reached the upward limit of its stroke, the charge in the compression space is exploded to impel the piston 6 downwardly. During the time the 50 piston 6 is being elevated, the piston 7 is being forced down by a previously exploded charge. As soon as the piston 7 has reached the lowermost limit of its stroke, the exhaust port 14 of the cylinder 3 is uncovered to exhaust the charge to atmospheric pressure and upon the upstroke of the piston 7 and consequently upon the up stroke of the piston 39, the charge in the chamber 49 of the pumping cylinder 4 is forced into the working 55 cylinder 3 and compressed by piston 7 into the compression space 10 of that cylinder and fired as before.

On each down stroke of the piston 46 oil is drawn into the chamber 48 and is again 60 forced out of that chamber on the up stroke

of the piston 46, thus insuring a continuous circulation of oil, the rapidity of which is dependent upon the speed of the engine and consequently the proper lubrication of bearing surfaces is assured. Heretofore in engines of this type, there has been some difficulty encountered in properly lubricating the stuffing box bearing 43 but with this construction where the chamber 48 functions as an oil duct chamber, ample lubrication is 75 obtained.

From the foregoing description, taken in connection with the accompanying drawings, it is thought the complete construction, operation and advantages of the invention will 80 be readily understood.

What I claim is:

1. In a two cycle engine, a pair of working cylinders and pistons, said cylinders having inlet and exhaust ports, a pumping cylinder and piston, a crank shaft, operative connections between said crank shaft and said pistons, said pumping cylinder having a pair of ports, a valved duct between each of said working cylinder inlet ports and one of said pumping cylinder ports respectively, an intake manifold, and valved connections between each of said ducts and said intake manifold. 95

2. In a two cycle engine, a crank case, a crank shaft, a pair of working cylinders mounted on said crank case, working pistons, connecting rods between said pistons and said shaft, a pumping cylinder, a partition dividing said pumping cylinder into 100 two sections, a pumping piston in one section dividing it into two chambers, said pumping cylinder having a port for each chamber, a cross head in the other section of said pumping cylinder, a piston rod between said pumping piston and said cross head piston, a connecting rod between said cross head piston and said crank shaft, said working cylinders having inlet and exhaust ports, a duct between the inlet port of one 105 working cylinder and one of the ports of said pumping cylinder, a second duct between the inlet port of the second of said working cylinders and the other port of said pump cylinder, means controlling the 110 flow of fluid from said ducts into the working cylinders, an intake manifold having communication with each of said ducts and check valves located at the places where said intake manifold communicates with 115 said ducts. 120

3. In a two cycle engine, a crank case, a crank shaft, a pair of working cylinders mounted on said crank case, working pistons, connecting rods between said pistons and said shaft, a pumping cylinder, a partition dividing said pumping cylinder into two sections, a pumping piston in one section dividing it into two chambers, said pumping cylinder having a port for each 125 130

chamber, a cross head in the other section of said pumping cylinder, a piston rod between said pumping piston and said cross head piston, a connecting rod between said 5 cross head piston and said crank shaft, said working cylinders having inlets and exhaust ports, a duct between the inlet port of one working cylinder and one of the ports of said pumping cylinder, a second 10 duct between the inlet port of the second of said working cylinders and the other port of said pump cylinder, means controlling the flow of fluid from said ducts into the working cylinders, an intake manifold 15 having communication with each of said ducts, check valves located at the places where said manifold communicates with said ducts, said pumping cylinder having a port leading into the space between said 20 partition and said cross head piston, oil eduction and induction pipes communicating with said last named port, and branch pipes for conveying oil from said eduction pipe to the bearing surfaces to be lubricated. 25

4. In an internal combustion engine, the combination of a pair of working cylinders having pistons and valved inlet ports, a pumping cylinder and piston, piston operating means, said pumping cylinder formed with a pair of ports, an intake manifold having an intake opening and charge conducting portions branching from said intake opening, a pair of ducts constructed and arranged to form independent avenues of flow from each of the manifold conducting portions respectively to a pump- 30

35

ing cylinder port and then reversely to the inlet port of a working cylinder, and a charge controlling means for said manifold. 40

5. In a device of the character described, the combination of a pair of working cylinders having pistons and inlet ports, a unitary pumping device comprising a pumping cylinder provided with a piston and a 45 pair of ports, piston operating means, a charge supply manifold having an intake opening, a duct between each of said inlet ports and one of the pumping cylinder ports respectively, said ducts independently communicating with the manifold at points removed from the intake opening and each adapted to conduct a charge from the manifold first to the pumping cylinder and then to a working cylinder and valvular controlling means for said charge supply manifold. 50

6. In an explosive engine, the combination of a pair of working cylinders having pistons and valved inlet ports, a pumping 60 device comprising a pumping cylinder provided with a pair of ports, a charge supply manifold and its intake opening, and a duct between each of said valved inlet ports and one of the pumping cylinder ports respectively, said ducts communicating with the manifold and each adapted so as to form an independent avenue of flow first to the pumping cylinder and then to a working cylinder, the point of communication between the manifold and a duct being located intermediate a valved inlet port and its related pumping cylinder port. 65
